WACLAW HARASIMIAK, OF CAMDEN, NEW JERSEY

MINE DRILL

Application filed July 5, 1928. Serial No. 290,545.

This invention relates to certain new and useful improvements in mine drills or augers and is intended for use by miners in drilling holes for setting powder blasts and the like and has for its primary object to provide improved screw feeding means for the drill comprising removable screw clamping jaws for engagement with the drill feed screw whereby the clamping screw 5 jaws may be removed and a new cooperating drill feed screw substituted of a different tread pitch whereby the drill feed screw may be fed forwardly at different speeds for accommodating the drill to wall strata of 10 different densities.

A further object of the invention is to provide a mine drill of the above kind wherein the drill rod feeding screw is supported in the frame that is capable of being 15 supported alone upon the side wall of a mine room or the like, or jointly supported upon the side wall and the floor.

With the above and other objects in view that will become apparent as the nature of 20 the invention is better understood, the same consists in the novel form, combination and arrangement of parts hereinafter more fully described, shown in the accompanying drawings and claimed.

30 In the drawings:—

Figure 1 is a side elevational view of a mine drill constructed in accordance with the present invention, the same being illustrated as supported on the side walls of a mine room or the like, the lower anchor or mounting rod being illustrated in a dotted line position with the lower end thereof intended for floor engagement;

Figure 2 is a top plan view of the mine 40 drill;

Figure 3 is a front elevational view;

Figure 4 is a rear elevational view;

Figure 5 is a fragmentary longitudinal 45 sectional view taken on line 5—5 of Figure 2 showing the expanding socket switch for the upper supporting rod of the drill frame;

Figure 6 is an enlarged detail sectional view taken on line 6—6 of Figure 2;

Figure 7 is an enlarged sectional view 50 taken on line 7—7 of Figure 6; and

Figure 8 is a fragmentary top plan view of the block supporting the jaws.

The drill comprises a supporting frame having side bars 1 connected at their opposite ends by rotatably adjustable shafts 2 and 3 at their upper and lower ends respectively, the shafts 2 and 3 being held in rotatably adjusted positions by cap nuts 4 threaded on the projecting ends of the shafts outwardly of the side bars of the 60 frame. The frame supports a block 5 intermediate the ends thereof and between the same in which a feed screw for a drill rod is mounted while devices are associated with the end cross shafts 2 and 3 for supporting 65 the frame.

The supports associated with the upper cross shaft 2 is shown more clearly in Figures 1 and 5 and comprises a rod 6 threaded at one end as at 7 and freely extends through 70 an opening in the head 8 of a screw pin that passes through a transverse opening in the shaft 2 for reception of the clamping nut 9, jamb nuts 10 threaded on the end 7 of the rod 6 at opposite sides of the head 8 being 75 adjustable thereon for holding the rod in longitudinally adjustable position. The forward end of the rod 6 is in the nature of an expanding wedge to be positioned in the manually chiseled opening 11 in the wall 12 80 shown in Figure 1. The expanding wedge end of the rod 6 comprises a socketed end portion 13 in which is slidably mounted the stub shaft 14 with the wedge head 15 upon the forward end thereof. The forward end of the end portion 13 of the rod 6 is annularly reduced and externally threaded as at 16 to receive the inner threaded end 17 of the longitudinally split expanding jaws 18 that enclose the wedge head 15. The stub shaft 14 is longitudinally shifted in the socketed end 13 of the rod 6, the rod end 13 having an annular enlargement externally threaded as at 19 with a longitudinally extending slot 20 formed in a side wall of the 95 enlargement and into which slot the pin 21 laterally projecting from the shaft 14 extends. The pin 21 extends into an inner annular groove 22 formed in the nut 23 so that upon rotation of the nut on the threads 100

19, the nut is shifted longitudinally of the rod end 13 to carry therewith the pin 21 and stub shaft 14. As the jaws 18 are formed of resilient metal, the same are forced open upon forward projection of the wedge head 15 and are automatically retracted when the wedge head 15 and shaft 14 are drawn into the socketed end 13 of the rod 6. The rod end 13 is illustrated in Figure 1 as mounted in the chiseled opening 11 in the wall 12 and supports the upper end of the frame that carries the drill rod feeding screw.

The support for the lower end of the frame comprises a rod 24 threaded at one end as at 25 and passing through an opening in the head 8 that is carried by the cross shaft 3, similar to the support for the rod 6. The shaft 3 is held in rotatably adjusted position by the nuts 4 as indicated by the dotted and full line positions of the rod 24 in Figure 1, while the longitudinal adjustment of the rod is accomplished by the jamb nut 10 cooperating with the apertured head 8. The forward pointed end of the rod 24 may be driven into an opening in the wall 12, or the end of said rod may engage the outer face of the wall, or further be disposed in the vertical position for engaging the ground or floor as illustrated by dotted lines.

30 The block or body 5 that supports the drill rod feeding screw carries side trunnions 26 supported in bearing slots 27 formed in the side bars 1 of the frame, the threaded projecting ends 28 of the trunnions 26 receiving cap nuts 29 for holding the block or body 5 in adjusted position. The slots 27 are of bayonet formation with the lateral extensions thereof preferably disposed at the upper ends so that the block may be supported 40 at different elevations.

The block 5 has an opening 30 axially thereof and rotatably receives the cylinder 31 provided with an annular groove 32 into which extends pins 33 from the stud screws 45 34 that permit rotary movement of the sleeve 31 and retain the same against longitudinally shifting movement. The sleeve 31 carries an inner longitudinally extending key 35 set into a groove in the sleeve and 50 extending into the central opening thereof. The sleeve is rotated through the medium of a gear train, the gear 36 being fixed to the projecting end of the sleeve 31 as shown in Figure 6 that is engaged by the pinion 37 55 journaled on the bracket arm 38 carried by the block 5, the bracket arm 38 further supporting the gear 39 meshing with the pinion and which gear 39 is operated by the handle 40. It will therefore be seen that upon rotation of the gear 39, the gear 36 will be rotated and such movement imparted to the sleeve 31.

A drill rod feeding screw 41 extends through the bore of the sleeve 31 and is provided with a longitudinal keyway 42 into

which the key 35 extends. The drill rod feeding screw 41 is rotated with the sleeve 31 and longitudinal screw feeding thereof is accomplished by the provision of two thread jaws 43 and 44 detachably carried by the block 5 and having the threads thereof of a pitch similar to the thread pitch of the drill rod feeding screw 41. The screw block thread jaws are connected together and are detachably mounted on the side of the block 5, opposite the gear 36, the opposed face of one of the thread jaws carrying a wear plate 45 laterally of the threaded portion 46. The thread jaws 43 and 44 are each provided with a radial slot 47 aligned with each other and through which slots a retaining screw bolt 48 extends for anchoring in the block 5. The opposite side edges of the two thread jaws 43 and 44 have an inter-engaging or dovetailed connection 44^a with side flanges of the block 5 whereby the two jaws are laterally slid into position on the block 5 to be retained by the screw bolt 48 as shown in Figure 8. The two thread jaws 43 and 44 have a spring connection therebetween and the threaded portions of said jaws are moved into engagement with the drill rod feed screw by a cam lever.

As shown in Figure 7, the two jaws 43 and 44 at opposite sides of the central threaded cavities are provided with aligned openings 49, the rod 50 disposed in said aligned openings having one end annularly enlarged and threaded as at 51 for threaded engagement with an opening at the outer end of the thread jaw 44 while the other end of the rod 50 clearly extends through the opening 49 in the thread jaw 43. An annular shoulder 48^a is formed on the wall of the opening 49 in the thread jaw 43 adjacent the outer end thereof and forms an abutment for one end of the coiled spring 52 that surrounds the rod 50 while the other end of the spring engages the closed outer end of the opening 49 in said jaw 44. The ends of the rod 50 that extend through the openings in the two thread jaws terminate outwardly of the thread jaw 43, the same being threaded at their ends as at 53 in threaded engagement with the angle ends of the yoke 54. A cam 55 is pivotally supported on the yoke 54 intermediate the ends thereof and carries an operating lever 56, the cam 55 being movable into engagement with the outer face or side of the jaw 43 as shown in Figure 6 for causing the two thread jaws 43 and 44 to move toward each other against the tension of the springs 52 for threaded engagement with the drill rod feed screw 41.

From the above detailed description of the invention, it is believed that the construction and operation thereof will at once be apparent, it being noted that the primary object of the invention is to provide interchangeable thread jaws 43 and 44, and an

interchangeable drill rod feed screw 41 so that thread jaws and a feed screw of a larger thread text may be utilized for boring a powder blast opening in a relatively soft wall while thread jaws and a feed screw of a finer thread pitch may be utilized for a harder wall of greater density. Rotation of the drill rod feed screw 41 is accomplished upon rotation of the gear 36 of the gear train that is fixed to the sleeve 31 carrying the longitudinal key 35 that extends into the groove 42 of the feed screw, these devices imparting rotary movement to the screw while longitudinal feeding movement there-of is accomplished by the thread jaws 43 and 44 which are locked to the stationary block 5 by the screw bolts 48, while they have threaded engagement with the fed screw as shown in Figures 6 and 7.

While there is herein shown and described the preferred embodiment of the present invention, it is nevertheless to be understood that minor changes may be made therein without departing from the spirit and scope 25 of the invention as claimed.

What I claim as new is:—

1. In a miners' drill, a frame, a block mounted on the frame, a pair of relatively movable thread jaws detachably mounted on the block, a drill rod feeding screw extending through the block and adapted to be engaged by the thread jaws, rotatable means on the block having a spline connection with the feed screw, springs normally separating the jaws, guide pins for the jaws surrounded by the springs, and means for closing the jaws against the spring tension thereon positioned exteriorly of the jaws and connected to the pins.

2. In a miners' drill, a frame, a block mounted on the frame, a pair of relatively movable thread jaws detachably mounted on the block, a drill rod feeding screw extending through the block and adapted to be engaged by the thread jaws, rotatable means on the block having a spline connection with the feed screw, said jaws having alined openings therein, pins anchored in the openings of one jaw and freely extending through the opening of the other jaw, a spring surrounding each pin and engaging the jaws to normally separate the same, a yoke connecting the pins outwardly of the jaws, and a cam lever pivoted on the yoke engageable with the jaws to close the same on the feeding screw.

3. In a miners' drill, a frame, a block mounted on the frame, a pair of relatively movable thread jaws detachably mounted on one side of the block, a drill rod feeding screw extending through the block and adapted to be engaged by the thread jaws, rotatable means on the block having a spline connection with the feed screw, spring devices for normally holding the jaws sepa-

rated and a cam carried by said spring devices for moving the jaws into clamping engagement with the feed screw, the spring devices including registering openings in the jaws, pins extending through the openings and anchored at corresponding ends in one jaw, a shoulder at the outer end of the openings in the other jaw, a coil spring surrounding each pin and confined by the anchored ends and shoulders, and said cam being attached to the projecting ends of the pins.

4. In a miners' drill, a frame, a block mounted on the frame, a pair of relatively movable thread jaws detachably mounted on one side of the block, a drill rod feeding screw extending through the block and adapted to be engaged by the thread jaws, rotatable means on the block having a spline connection with the feed screw, spring devices for normally holding the jaws separated and a cam carried by said spring devices for moving the jaws into clamping engagement with the feed screw, the spring devices including registering openings in the jaws, pins extending through the openings and anchored at corresponding ends in one jaw, a shoulder at the outer end of the openings in the other jaw, a coil spring surrounding each pin and confined by the anchored ends and shoulders, a cross yoke on the projecting ends of the pins and said cam being attached to the cross yoke.

In testimony whereof I affix my signature.
